DEVICE FOR AUTOMATICALLY CONTROLLING THE FILLING OF RESERVOIRS, TANKS, AND THE LIKE

Emile Piquerez, St. Cloud, France

Application July 16, 1936, Serial No. 91,012
In France July 25, 1935

8 Claims. (Cl. 226—120)

The present invention relates to a connecting device or union for use in the filling of receptacles, reservoirs, tanks and the like, which is adapted to operate in such a manner as to automatically stop the inlet of the liquid which passes through it when the liquid in the receptacle reaches a predetermined level, the said connection either being combined or not combined with means for interchanging the atmospheres of the said receptacle 10 and that from which the liquid is supplied.

Apparatus according to the invention is characterized by the feature that the liquid inlet conduit is provided with a closure member or valve controlled by the fall in pressure created in the apparatus by a suction device operated by the liquid flow. The fall in pressure created by this device is applied to a chamber having at least one movable wall or partition operatively connected with the closure member or valve, the said 15 chamber communicating with the interior of the receptacle to be filled, through a passage open at the level to which the receptacle is to be filled with liquid, in such a manner that the entry of the liquid into the said passage brings about an increase of the suction effect in said chamber, up to the value necessary to cause the closing of the liquid inlet by the closure member or valve.

The above mentioned passage is advantageously provided with an appropriate member having a 20 constricted opening to hinder the entry of the liquid, in such a manner as to obtain the maximum fall in pressure in the chamber at the moment when the liquid reaches the inlet opening of the passage. To the same end, the latter 25 may be provided with a closure member or valve controlled by the flow of the liquid, such, for example, as a float valve.

In the preferred constructional forms of the apparatus, the suction device operated by the 30 liquid flow comprises a horn-like tube, and a particular characteristic of the invention is that the lower opening of the tube is arranged below the inlet opening of the above mentioned passage, in such a manner that a little before the liquid 35 has access to said passage, the outlet orifice of the horn-like tube is submerged and the latter consequently operates with the best efficiency.

In certain particular cases, when the connection device or union is intended for the transfer 40 of dangerous volatile liquids, for example, hydrocarbons, it may comprise a gas outlet conduit for the exchange of the atmospheres between the receptacle in process of being filled and that in course of emptying. This modified arrangement may also constitute safety means, en-

suring the closing of the liquid inlet conduit, in the event of excessive pressure arising in the receptacle being filled for any cause whatever. To this end, the gas outlet opening or openings of the receptacle to be filled, in communication with the gas return conduit, are situated at a high level or at least at the same level as that of the lower opening of the passage leading to the suction chamber. On the said gas return conduit is arranged a pressure chamber opposite to the suction 10 chamber, that is to say, situated on the other side of the movable control member for the liquid feed pipe closing device.

In this case, obviously, the connection device or union can be provided with a joint in leak-proof connection with the receptacle to be filled but when the connection device for union does not comprise an atmosphere-exchanging arrangement, a leak-proof connection is unnecessary. Thus the invention provides a further advantage 20 over known devices for limiting the replenishment of receptacles and the like.

The movable wall or partition of the suction chamber which, as mentioned above may, in certain cases, be common to the said suction 25 chamber and to a pressure chamber, may consist of piston or, preferably a membrane or equivalent. The said movable wall or partition can be attached directly to the closure member or valve, but, preferably, it cooperates with a catch which 30 normally holds the closure member or the valve open against the action of a spring (which may be previously loaded by hand) in such a manner that the closing of said member or valve may be instantaneous.

One simple and efficacious construction comprises a pivoted lever having one end arranged to be displaced by the piston, membrane or equivalent and having its opposite end pivoted to a catch, against which a shoulder on the rod of 40 the closure member or valve, is adapted to abut, said catch being guided for movement in a direction intersecting the axis of the said rod.

The annexed drawings show, by way of example, various constructional forms of the invention 45 diagrammatically and also one construction in greater detail.

Figure 1 shows one construction in diagrammatic elevation;

Figure 2 shows another construction in a similar manner;

Figure 3 shows, in diagrammatic elevation, the addition to one of the above constructions of a gas exchange conduit;

Figure 4 shows diagrammatically the combina- 55

tion of the apparatus shown in Fig. 1 with a gas exchange conduit constituting a safety device;

Figure 5 is a vertical section of one practical constructional form of an apparatus as shown 5 in Fig. 4; and

Figure 6 shows, in section, a lengthening member capable of being used on the apparatus shown in Fig. 5.

Referring to the drawings:—

- 10 In Fig. 1 which shows a simple construction of replenishment-limiting union or connection, numeral 1 designates a downwardly enlarging or horn-like tube and 2 an injector nozzle cooperating with said tube and connected to a small 15 liquid inlet conduit 3. A valve 4 is arranged in the conduit 3 and is provided with a rod 5 which is attached at its opposite end to the movable wall 6 of a chamber 7.
- 10 The movable wall consists, for example, of a 20 membrane which, on its inner face, is subjected to the fall in pressure produced by the flow of liquid into the tube, the chamber 7 being connected to the body 2 by a conduit 8. A spring 9, tends constantly to maintain the valve 4 open against the 25 action of the fall in pressure in the chamber 7, said valve, moreover being screened normally from the inlet pressure of the liquid by a deflector 10. On its external face, the membrane 6 is subjected to atmospheric pressure.
- 30 A small passage 11 descends from the chamber 7, the lower opening 12 of the passage being adapted to fix the filling level of the liquid in the receptacle R. The outlet opening 1a of the tube 1 is situated below the level of the opening 12 in 35 such a manner that it is submerged during the useful period of the operation. The positioning of the openings 12 and 1a with respect to the receptacle R is assumed to have been fixed, for example, by a collar 13 which bears on a filling tube 14 of the receptacle.

40 It will be easily understood that when the tube functions, flow of air or gas according to the contents of the receptacle R, will be produced in the direction 12—11—8—2, and, consequently, that a certain fall in pressure will occur in the chamber 7. The fall in pressure will increase when the liquid has flowed into the opening 12. In order that the increase in the fall in pressure may be 45 very appreciable and that its final value may conform to the object sought, a diaphragm 15 having a constricted opening 16 has been arranged at the bottom of the tube 11.

50 In these conditions, when the filling level of the liquid in the receptacle R is attained, the fall in pressure produced in the chamber 7 causes the displacement of the membrane 6 against the action of the spring 9, the closing of the valve 4 and, consequently, the stoppage of the flow of liquid into the nozzle 2 being brought about at 55 the same time.

55 The construction shown in Fig. 2 is distinguished solely from the preceding construction in that the diaphragm 14 with its calibrated orifice 16 is replaced by a valve 17 provided on a float 18, 60 which is arranged in a chamber 19 provided on the tube 11. As soon as the liquid closes the opening 12, the sharp increase in the fall in pressure in the chamber 7 causes the liquid to rise in the chamber 19, whereby the valve 17 is moved on its seat 20. As the small tube 11 is thus completely closed, the fall in pressure in the chamber 7 is 65 high, so that the valve 4 is caused to move to its seat. As the operation is very rapid, the filling level of the liquid in this case can be considered 70 as being in the plane of the opening 12.

The apparatus shown in Fig. 3 is formed by connecting an apparatus such as shown in Fig. 1 or Fig. 2 with a conduit 21 for the evacuation of the atmosphere in the receptacle R in the course of filling. The said conduit terminates at its upper end in a small tube 22 which can receive piping leading to the receptacle being emptied so that there may thus be an exchange of atmosphere between the two receptacles.

At its lower end, the mouth 23 of the conduit 10 21 is at a higher level than that of opening 16 which marks the filling level of liquid in the receptacle R.

In the modification shown in Figure 4, the 15 membrane 6 forms part of the wall of the conduit 21 which, unlike the chamber 7, forms a pressure chamber. The connection of the apparatus with the receptacle R between 13 and 14 is necessarily leak-proof and is furnished with a joint 24.

Assuming that the replenishment-limiting device 20 previously described may not have functioned, for example, because the rate of flow of the liquid has been insufficient to produce a fall in pressure capable of closing the valve 4, the liquid will rise in the conduit 21 and will act on 25 the membrane in the direction to close the valve 4.

Again assuming that the apparatus has not 30 functioned, if the piping used for exchange of atmosphere between the two receptacles is closed, then the pressure of the gas in the conduit 21 will 35 act to displace the membrane in the direction to close the valve.

In any case, the pressure of the gases in the reservoir will thus not be able to attain value 35 dangerous for the reservoir.

The construction shown in Fig. 5, arranged, 40 for example, for use in the filling of petrol tanks of aeroplanes or other vehicles, comprises a casing 51 provided with an inlet tube 52 in which a deflector 53 serves as a support, for a valve 54 45 during the operation of the apparatus. The tube 52 communicates with an injection nozzle 55 50 communicating with the tube 56. The upper end of the tube 56 opens into a chamber 57 in which a membrane 58 is arranged and is held in position by a cap 59 provided with a handle 60 for the transport of the apparatus. A chamber 61 is formed in the cap 59 opposite to the chamber 57 on the other side of the membrane 58, the chamber 55 communicating through channels (not shown on the drawings) with the internal chamber 62 in the tubular foot 63 of the apparatus which has large openings 64 providing communication with the atmosphere of the reservoir which is to be filled. The gases from the reservoir can thus reach the chamber 61, which is provided with a small outlet branch 65, whereby it may be connected to the reservoir in course of emptying for the exchange of atmospheres between the two reservoirs. The tubular foot 63 has a joint 60 66 consisting, for example, of a ring of rubber arranged to be applied on the top of the filling tube of the reservoir so as to fulfill the function of the joint 24 shown in Fig. 4.

The chamber 57 below the membrane 58 also 65 communicates with the atmosphere of the reservoir during the filling of the latter by means of a small passage 67 formed in the casing of the tube 56 and corresponding to the conduit 11 shown in Figs. 1 to 4.

The lower opening 67a of the passage 67, which in practice fixes the filling level, is situated below the upper edge of the openings 64, so as to avoid an excess of pressure in the reservoir.

The passage 67 may be provided at any point 70 75

whatever in its height with a plug or diaphragm having a calibrated opening to impede the flow of the liquid and thus to bring about an increase of the fall in pressure in the chamber 57.

It will be easily seen that during the filling of the reservoir, the tube creates in the chamber 57 a fall of pressure which is made up in proportion by the gases in the reservoir being carried up through the small passage 67. As soon as the lower opening in the latter is closed by the liquid, which will flow in the passage with greater difficulty than the gases, the fall of pressure in the chamber 57 will increase and will be able to displace the membrane. In order to obtain the closing of the valve 54, in consequence of the displacement of the membrane, the following arrangement can be advantageously used.

The valve 54 is subjected constantly to the action of a spring 70, arranged in the deflector 20 53, which tends to force it on its seat 71. The seating of the valve is, however, normally prevented by a small catch 72 against which the tail 73 of the valve rod is adapted to abut. The catch is provided with a roller 74, which bears on a 25 rolling track 75 perpendicular to the direction of the axis of the valve rod. At its upper end, the catch 72 is pivoted at 76 to a lever 77 hinged at 78 and carrying beyond the latter a roller 79, which is adapted to bear against the bottom 30 face of a central member 80 on the membrane 58 under the action of a spring 81.

During filling, the membrane is lifted by the roller 79, the lever 77 is inclined and the lower end of the catch 72 is neatly engaged behind the adjacent face of the tail 73 of the valve rod.

When the filling level of the liquid is reached the fall of pressure in the chamber 57 causes the lowering of the membrane 58 and, consequently, the ascent of the catch 72 and roller 74. As the valve 54 is now freed, it is forced sharply 40 on its seat under the action of the spring 70. It will be noted that as soon as the valve is disengaged from the deflector 53, it is assisted in its closing movement by the pressure of current of liquid.

When the valve 54 is closed, the fall in pressure in the chamber 57 is stopped and spring 81 causes the membrane 58 to be lifted again and the catch 72 to be lowered, so that it will engage 50 in an annular groove 82 in the valve rod.

In order that the apparatus may be able to function again after having been removed from the reservoir, it is necessary to re-set it. To this end, there is used, for example, a push rod 55 83, connected to an external knob 84 which, under the action of a spring 85, occupies normally a withdrawn position. Any suitable means is provided to ensure tightness against leakage between the member 86 and the push rod 83. The 60 resistance which will be opposed by a stuffing box, for example, is not to be entertained, since the push rod will be actuated by hand. If, on the contrary, the valve rod itself had been prolonged, the means for ensuring tightness would have been 65 incompatible with the liberty of its movements. In the arrangement adopted, assuming that there is a slight escape of liquid around the valve rod from the chamber 52 into the chamber 57, it will be sucked back by the tube 56.

The actuation of the push rod 83 causes the 70 forward movement of the tail 73 of the valve 54 which, through the inclined face 73a on the valve rod, will act to lift the catch 72, the lower end of which is also inclined in such a manner 75 that the catch will be able to pass from the

other side of the swelling of the tail 73 and retake the position shown in Fig. 5. Thereafter, the push rod can be moved in the reverse direction.

If, for any reason, the operation of the replenishment-limiting device which has just been described does not take place and if the liquid continues to rise in the reservoir until the ports 64 have been closed, then the pressure of the atmosphere of the reservoir would be raised and 10 the liquid which is rising in the chambers 62 and 61 would act to force the membrane to deflect downwardly by means of the pressure acting on its upper face before the pressure in the reservoir had reached a dangerous value. 15

Finally, it will be advantageous, as shown on the drawings, to provide the membrane with a guide 87 leading to the exterior of the apparatus, so that in case of locking or wedging in the interior of the apparatus, the valve can always 20 be closed by pushing on the rod 87.

The lengthening member shown in Fig. 6 permits the apparatus to be applied to reservoirs having long filling tubes. The central tube 88 of the lengthening member is screwed on to the 25 end of the tube 56, whilst the member 89 which surrounds it forms a joint with the ring 90 of the said tube. The conduit 67a therefore communicates with the space between the two members 88 and 89. The filling level of the liquid 30 is then appreciably that of the lower inlet of the member 89. The latter is centered on the member 88 for example, by ribs 88a and by a six-sided mouth 89a which permits the screwing of the member 88 on to the tube 56. 35

It follows that the invention is not limited to the constructional form described and shown of which it comprises all variations.

I claim:

1. Level limiting connection for filling receptacles with liquid, comprising, a casing having a liquid conduit comprising an inlet tube, a downwardly enlarging outlet tube, and an injector nozzle connecting said inlet tube with said outlet tube, a valve for closing said conduit, said casing forming a chamber having a movable wall comprising a diaphragm, said casing forming an inclined annular air conduit of small cross section communicating with said liquid conduit between the injector nozzle and outlet tube thereof, and with said chamber, the lower end of the outlet tube emptying freely into the receptacle being filled, said casing having an air passage having its upper end opening into said air conduit and its lower end opening to the receptacle being filled, said lower opening being situated at a higher level than the discharge end of said liquid outlet tube, and means mechanically connecting said diaphragm with the valve to close said valve through the effect of the reduction of pressure produced in the chamber when the liquid in the receptacle closes the lower opening of said air passage. 40 45 50 55 60 65

2. Level limiting connection for filling vessels with liquid, comprising a casing having a liquid inlet conduit, a stop valve for said conduit, said valve being disposed to close by movement in the same direction as the liquid flow, a deflector behind said valve to shield it from the pressure of the flowing liquid, a chamber, having a movable wall, a rod directly connecting said wall to said stop valve so that movement of said wall, responsive to a pressure reduction, causes a movement of said stop valve towards its seat, and thus permit the liquid to add its action for 70 75

- closing the valve, a blast tube in said liquid conduit to create a suction in said chamber, said casing being formed with a passage connecting said chamber with the atmosphere of the vessel being filled, said passage having an orifice at its lower end, said orifice having means for restricting the flow of the liquid into said passage and a spring for normally holding said movable wall and said stop valve in the open position.
3. Level limiting connection for filling vessels with liquid, comprising a frame having a liquid inlet conduit, a shut-off valve in said liquid conduit, a spring pressing on said valve in the closing direction, a catch for holding said valve open against the action of said spring, a pressure-reduction chamber having a movable wall consisting of a diaphragm, a lever, a medial hinge for said lever, one end of said lever being arranged in contact with the center of said diaphragm, and the other end being hinged on said catch so that the latter moves backwards and releases said valve when said diaphragm effects an inward movement, a spring opposing the inward movement of said diaphragm and holding said catch engaged, a blast tube arranged in said liquid inlet conduit and sucking in the pressure-reduction chamber, and a conduit of small cross-section connecting said pressure-reduction chamber with the atmosphere of the vessel being filled, the lower orifice of said small conduit determining the filling level, and means for bringing said valve into the position in which it is engaged by said catch.
35. 4. Level limiting connection for filling vessels with liquid, comprising a frame having a liquid inlet conduit, a shut-off valve in said liquid conduit, a spring pressing on said valve in the closing direction, a catch for holding said valve open against the action of said spring, a pressure-reduction chamber having a movable wall consisting of a diaphragm, a lever, a medial hinge for said lever, one end of said lever being arranged in contact with the center of said diaphragm and the other end being hinged on said catch so that the latter moves backwards and releases said valve when said diaphragm effects an inward movement, a spring opposing the inward movement of said diaphragm and holding said catch engaged, a blast tube arranged in said liquid inlet conduit and sucking from the pressure-reduction chamber, and a conduit of small cross-section connecting said chamber with the atmosphere of the vessel being filled, the lower orifice of said conduit determining the filling level, a plunger sliding oppositely to said valve, a retracting spring for said plunger, and another plunger outwardly fixed to the center of said diaphragm to enable said catch to be disengaged at will.
60. 5. Level limiting connection for filling vessels with liquid comprising a frame having a liquid inlet conduit, a stop valve for said conduit, means, having two oppositely directed pressure responsive surfaces, for controlling said valve, means for generating a fall of pressure by the flow of liquid in said conduit and applying said reduced pressure to one of said pressure responsive surfaces

when the level in the receptacle being filled reaches a predetermined level, and means for applying the pressure of the receptacle being filled to the other of said surfaces.

6. Level limiting connection for filling vessels with liquid, comprising a frame having a liquid inlet conduit, a stop valve for said conduit, a chamber having a movable wall, means for controlling said valve from said movable wall, a blast tube in said liquid conduit to create a suction in said chamber, a conduit connecting said chamber with the atmosphere of the vessel being filled through a lower orifice determining the filling level, and a second chamber formed on the other side of said movable wall of the first-mentioned chamber, said second chamber communicating on the one hand with the atmosphere of the vessel, and on the other hand with an orifice to be connected with the atmosphere of the vessel supplying the liquid.

7. Level limiting connection for filling vessels with liquid, comprising a frame having a liquid inlet conduit, a stop valve for said conduit, a chamber having a movable wall and means for controlling the closing of said valve from said movable wall, a blast tube in said liquid conduit, and adapted to produce a suction in said chamber, a conduit for connecting said chamber with the atmosphere of the vessel being filled, said conduit opening into the vessel through a lower orifice which determines the filling level, a second chamber on the opposite side of the movable wall from the first chamber, said second chamber communicating, on the one hand with the atmosphere of the vessel through an orifice located at a level at least as high as the level of the lower orifice of the conduit leading from said first chamber, and on the other hand with an orifice adapted to be connected with the atmosphere of the cistern supplying the liquid.

8. Level limiting connection for filling vessels with liquid, comprising a frame having a liquid inlet conduit, a shut-off valve in said liquid conduit, a spring pressing on said valve in the closing direction, a catch for holding said valve open against the action of said spring, a chamber having a movable wall consisting of a diaphragm, a lever, a medial hinge for said lever, one end of said lever being arranged in contact with the center of said diaphragm and the other end being hinged on said catch so that the latter moves backwards and releases said valve when said diaphragm effects an inward movement, a spring opposing the return movement of the diaphragm, a blast tube arranged in said liquid inlet conduit of small cross-section connecting said chamber with the atmosphere of the vessel being filled, the lower orifice of said conduit determining the filling level, and a second chamber formed on the other side of the movable wall of the first chamber, said second chamber communicating with the atmosphere of the vessel being filled, and means for hermetically sealing the connection with the vessel.

EMILE PIQUEREZ. 65
